UNITED STATES PATENT OFFICE.

SAMUEL BERMAN, OF CHICAGO, ILLINOIS.

DISPLAY CASE.

Application filed April 30, 1923. Serial No. 635,603.

To all whom it may concern:

Be it known that I, SAMUEL BERMAN, a citizen of Lithuania (having declared his intention of becoming a citizen of the 5 United States), residing at Chicago, in the county of Cook and State of Illinois, have invented a certain new and useful Improvement in Display Cases, of which the following is a full, clear, concise, and exact description, reference being had to the accompanying drawings, forming a part of this 10 specification.

My invention relates to display cases, and 15 more particularly to refrigerated display cases.

It is a purpose of my invention to provide a display case suitable for displaying food or other articles that are to be refrigerated, or for any other purpose where it is desirable 20 that a case is provided with doors therein that are so mounted that any one of said doors may be opened without interfering with the other doors. Thus any 25 number of doors may be opened simultaneously.

In the preferred embodiment of the invention shown, the doors are mounted slidably in suitable guideways, so that the same 30 can be moved from a closed position to an open position and remain in such open position without interfering with the adjacent doors. The guides preferably comprise an inclined portion with which the doors engage when in closed position, and a substantially horizontal portion with which the 35 doors engage when in opened position.

It is also a purpose of the invention to provide means for preventing pulling of 40 the doors out of the guideway, said means being preferably in the form of cooperating stop members on the guides and the doors.

Other objects and advantages of the invention will appear as the description of 45 the accompanying drawings proceeds. However, I desire to have it distinctly understood that I do not intend to limit myself to the exact details shown or described, but that I intend to include as part of my invention all such obvious changes and 50 modifications of parts as would occur to a person skilled in this art and as would fall within the scope of the claims.

In the drawings.

Fig. 1 is a fragmentary plan view of a 55 display case made in accordance with my invention;

Fig. 2 is a vertical transverse sectional view thereof;

Fig. 3 is a section taken on the line 3-3 60 of Fig. 2; and

Fig. 4 is a section taken on the line 4-4 65 of Fig. 2.

Referring in detail to the drawings, the display case comprises a shelf-like base member 5, a rear wall 6 and a top wall portion 7 of any suitable material, such as wood, marble, or any other opaque material. Mounted on the member 5 are bracket members 8, said bracket members being held in position by means of the clamping brackets 9 70 provided with the screw clamps 10 engaging the member 5. The members 8 are provided with horizontally extending portions 11, and mounted on said members 8 and 11 are glass plates 12 and 13, said plates 12 being held in position on the members 8 by means of the clamping strips 14 held in place by means of the screws 15, as shown in Fig. 4. Felt strips 16 are provided between the members 8 and 12 and 75 the members 14 and 12 to make an airtight joint. In a similar manner the plate glass members 13 are held in position by means of the clamping strips 17.

The bracket members 8 are provided with 80 inclined extensions 18 extending downwardly at an angle from the portion 11, and the portion 11 and the portion 18 are provided with flanges 19 and the portion 11 is provided with flanges 20. The flanges 19 on 85 the portions 11 and 18 of the member 8 are joined by a curved portion 21, and are provided with laterally extending lugs 22. The lower end portion of the member 18 is provided with a horizontal flange portion 90 23, a vertically extending portion 24 and a securing portion 25 for securing the same to the member 7 by means of the members 26. The members 19 and 20 form guideways on the portions 11 and the flanges 19 100 on the portions 18 form supports for the door frames 27, which are provided with glass panes 28 if desired. Said frames are provided with beveled portions 29 and 30 at the lower ends thereof, which are adapted 105 to engage snugly with the portions 23 and 24 of the bracket members. Said frame members 27 are also provided with suitable stops 31 which are adapted to engage with the stop lugs 22 previously described.

It will be seen that when the members 27 110 are in the position shown in full lines in

Fig. 2, the same will close the display case as clearly shown in Fig. 1, closing the space between the glass panes 13 and the portion 7 of the case.

It will also be seen that by grasping the handles 32 provided on the doors, the same can be readily moved from the full line position shown in Fig. 2 to the dotted line position shown in said figure. When the doors are moved to the dotted line position shown in Fig. 1, the same will be in such a position that access can be readily had to the interior of the display case, and it will also be seen upon reference to Fig. 1 that when the doors are in such position they will not interfere with each other, and any or all of the doors can be opened as desired.

It will be further noted from Fig. 2 that when the doors are in the dotted line position, the same will remain in such position unless moved again to the full line position, due to the fact that the doors are then in a horizontal position, and can easily be maintained in such position.

In order to prevent pulling the door too far outwardly when the same is being moved into position to close the same, the cooperating stops 22 and 31 are provided, said stops acting to limit the movement of the door by being so positioned that the same will not interfere with the engagement of the beveled faces 29 and 30 with the portions 23 and 24.

It is to be understood that the case described above may be refrigerated in any desired manner.

Having thus described my invention, what I desire to claim and secure by U. S. Letters Patent is:

1. In a display case, guide members comprising substantially horizontally extending straight portions, inclined straight portions and curved portions joining said horizontally extending and inclined portions, and doors slidably mounted between said guide members, said guide members having lower flanges comprising horizontally extending guiding and supporting flange portions, inclined guiding and sealing flange portions, inclined guiding and sealing flange portions and curved guiding flange portions joining said horizontally extending flange portions and said inclined flange portions, said doors sliding on said flanges.

2. In a display case, guide members comprising substantially horizontally extending straight portions, inclined straight portions and curved portions joining said horizontally extending and inclined portions, and doors slidably mounted between said guide members, said guide members having lower

flanges comprising horizontally extending guiding and supporting flange portions, inclined guiding and sealing flange portions and curved guiding flange portions joining said horizontally extending flange portions and said inclined flange portions, said doors sliding on said flanges and upper horizontally extending flanges on the horizontal portion of said guide members for retaining said doors in horizontal position.

3. In a display case, guide members comprising substantially horizontally extending straight portions, inclined straight portions and curved portions joining said horizontally extending and inclined portions, and doors slidably mounted between said guide members, said guide members having lower flanges comprising horizontally extending guiding and supporting flange portions, inclined guiding and sealing flange portions and curved flange portions joining said horizontally extending flange portions and said inclined flange portions, said doors sliding on said flanges, said guide members having laterally extending stop members thereon and depending stop members on said doors cooperating therewith.

4. In a display case, guide members comprising substantially horizontally extending guide portions, inclined guide portions and curved portions joining said horizontally extending and inclined portions, and doors slidably mounted between said guide members, said guide members having lower flanges comprising horizontally extending flange portions, inclined guiding and sealing flange portions and curved flange portions joining said horizontally extending portions and said inclined portions, said doors sliding on said flanges and upper horizontal flanges on said guide members for retaining said doors in horizontal position, said upper flanges terminating opposite the curved portions of said lower flanges.

5. A frame member for display cases comprising a horizontally extending portion having upper and lower laterally extending guide flanges, a portion inclined at an oblique angle to said horizontal portion having a lower guide flange, a curved portion having a lower curved guide flange joining the lower flanges on said inclined and horizontal portions of said frame member and means on opposite ends of said frame member for securing the same in position.

In witness whereof, I hereunto subscribe my name this 23rd day of April, A. D., 1923.

SAMUEL BERMAN.
